UNITED STATES PATENT OFFICE

117,334

DESIGN FOR A COMBINED FLOWER HOLDER AND MIRROR BASE

Horace A. Fuld, New York, N. Y.

Application June 28, 1939, Serial No. 85,729

Term of patent 7 years

To all whom it may concern:

Be it known that I, Horace A. Fuld, a citizen of the United States of America, residing in New York city, in the Borough of Manhattan, county and State of New York, have invented a new, original, and ornamental Design for a Combined Flower Holder and Mirror Base, of which the following is a specification, reference being had to the accompanying drawing, forming part thereof, wherein

I claim:

The ornamental design for a combined flower holder and mirror base, substantially as shown.

HORACE A. FULD.
